UNITED STATES PATENT OFFICE.

WILLIAM W. HOBE, OF NEW YORK, N. Y.

DESIGN FOR A BUTTON.

58,485.

Specification for Design.

Patented July 26, 1921.

Application filed September 29, 1920. Serial No. 413,618. Term of patent 3½ years.

To all whom it may concern:

Be it known that I, WILLIAM W. HOBE, a subject of the Government of Germany, residing at New York city, in the county of New York and State of New York, have invented a new, original, and ornamental Design for Buttons, of which the following is a specification, reference being had to the accompanying drawing, forming part thereof, in which—

Figure 1 is a face view of a button showing my new design;

Fig. 2 is an end view thereof; and

Fig. 3 is a side elevation thereof.

I claim:

The ornamental design for a button as shown.

WILLIAM W. HOBE.
